UNITED STATES PATENT OFFICE.

JOHN MILLS, OF WYOMING, NEW JERSEY, ASSIGNOR TO WESTERN ELECTRIC COMPANY, INCORPORATED, OF NEW YORK, N. Y., A CORPORATION OF NEW YORK.

MEANS FOR AND METHOD OF WAVE TRANSMISSION.

1,412,567.

Specification of Letters Patent. Patented Apr. 11, 1922.

Application filed December 30, 1916. Serial No. 139,741.

To all whom it may concern:

Be it known that I, JOHN MILLS, a citizen of the United States, residing at Wyoming, in the county of Essex and State of New Jersey, have invented certain new and useful Improvements in Means for and Methods of Wave Transmission, of which the following is a full, clear, concise, and exact description.

10 This invention relates to elimination or reduction of static or other similar interference.

It is well-known that when an impulsive or static disturbance is received by a high frequency signaling system, a disturbing noise is produced in the telephone receiver associated with the receiving system.

15 The present invention has for an object to provide a method and means for eliminating the noise in the receiver due to the reception of disturbing waves of static or other origin.

This is accomplished, first, by converting the high frequency signal and disturbing 25 currents into audio frequency signal currents, which will have superimposed thereon audible frequency noise currents, due to the disturbing waves, and second, by suppressing the audible frequency noise currents.

30 In a more specific aspect the invention provides for receiving the high frequency signal and impulsive disturbances in a circuit having a single natural period of vibration, as distinguished from prior receiving 35 circuits, having two natural periods, which are differentially related to the signal receiving device, as in the patent to De Forest, No. 759,216. In the present invention the elimination of the audio frequency disturbing

40 currents depends upon the difference in the character of audio disturbing currents and the audio signal currents, and advantage is taken of this difference in character to suppress the former. With reference to the

45 audio frequency, the duration of the disturbance due to a static wave or other wave having a similar wave form is so short that it is substantially a pulse. It is well known that when an electromotive pulse strikes a

50 resonant network, such as a filter of the well-known Campbell type, currents of natural oscillation are established corresponding to the periods of free vibration of the resonant network or filter. According to the present

invention the audio frequency currents are supplied to a filter which has its modes of free vibration critically damped, so that when a pulse strikes the filter, the latter delivers not oscillations, but pulsations or pulses, as the current rises to a maximum and drops to zero without reversing, due to the critical damping. The amplitude of the pulses which a filter receives is reduced by means of the damping, and a plurality of filters are provided in order that there may be a sufficient reduction. Audio frequency signaling currents, however, acting as forced oscillations, are transmitted through the filters sufficiently well, so that the signal currents are selectively received free from disturbances due to the interfering currents.

For a detailed description of the invention, reference may be made to the drawing, in which the figure shows diagrammatically a system embodying the invention.

To aid in reading the drawings each audion is provided with an auxiliary reference letter having the following significance: G=generator, D=detector, U=unilaterally conductive.

Referring to the drawing, the antenna 1 is coupled by means of the transformer 2 to the input circuit of a detector 3, which may be of the audion type as shown. The input circuit of the detector 3 is tuned by means of the variable condenser 4 to the high frequency to be received. The antenna is very loosely coupled to the circuit containing the condenser 4. As a single resonant circuit is provided between the antenna 1 and the detector 3, it will be apparent that, under these circumstances, this receiving system has substantially one high frequency natural period of vibration. Coupled to the input circuit of the detector 3, by means of the circuit 5, is a generator 6 of high frequency oscillations.

This generator 6 is shown as comprising an audion having its input and output circuits coupled in a known manner, but the invention is not restricted to the use of this particular type of generator. For receiving telegraph signals, the generator 6 supplies oscillations of a frequency different from the frequency to which the input circuit of the detector 3 is resonant. This is commonly known as heterodyne reception. If it is desired to receive wireless telephone messages, the generator 6 supplies oscillations of the

same frequency as that for which the input circuit of detector 3 is tuned. This is known as the homodyne method of reception.

Between the detector 3 and the signal receiving device 7, is connected the means for substantially freely transmitting the audio frequency signal currents while highly attenuating and substantially extinguishing the audio frequency disturbing currents. As described above, this means comprises a plurality of filters, F^1 , F^2 , F^3 and F^4 , of the well-known Campbell type. As shown, each one of these filters has three sections, although each filter may have a single section only or may have more than three sections if desired. Furthermore, the filters need not all have the same number of sections. Each of the filters or resonant networks having three sections will have three modes or periods of free vibration, the latter, however, being critically damped by means of the resistance elements 8, 9, 10 and 11. The natural frequencies of the filters may have any desired values within the audio frequency range. The values of the electrical constants of the filters may assume a great variety of different values, which may be computed by well-known formulæ. The maximum amplitude of any natural oscillation established in the first section of any filter will be inversely as the inductance of the filter element regardless of the number of sections, so that several sectional filters instead of a single filter having a larger number of sections is to be preferred. In order to prevent reaction between the filter F^1 and the circuits between it and the detector 3, a unilateral device 12, which may be of the audion type as shown, is provided. This unilateral device 12 has its input circuit tuned by means of the condenser 13 to the audio frequency range to be received, whereby high frequency currents are suppressed and prevented from reaching the filters.

The circuit containing condenser 13 may be flatly tuned by means of resistance, particularly where it is necessary to cover the audible range of speech as in telephony. It is to be noted that the resistance 8 is included in the output circuit of the unilateral element 12 and the resistance 11 is in the input circuit of the unilateral device 14. Other unilateral elements, 14, between filters F^1 and F^2 ; 15, between filters F^2 and F^3 ; 16, between filters F^3 and F^4 ; 17, between the signaling device 7 and the filter F^4 , are provided for similar purpose, i. e., to transmit current from the detector 3 to the signaling device 7 unilaterally and to prevent reaction between the various filters and networks shown.

As described above, it will be apparent that the audio frequency interfering currents supplied by the detector 3 will be converted into pulses by means of the filters

F^1 , F^2 , F^3 and F^4 , which have their natural modes of vibration critically damped. The interfering currents are successively attenuated in each filter, and the plurality of filters connected in tandem insure that the attenuation may be sufficient to reduce the interfering currents to a negligible value. The audio frequency signaling currents, however, delivered by the detector 3, acting as forced vibrations, are freely transmitted from the several filters, so that these signaling currents are received by the signal device 7 to the exclusion of the interfering currents.

What is claimed is:

1. The method of eliminating static disturbance in a receiving circuit having a single natural high frequency period which consists in converting the high frequency currents into audio frequency noise and signal currents, and successively attenuating said noise currents.

2. In a wave transmission system, a plurally branched electrical network including inductance and capacity elements, means for supplying electrical energy to said network comprising an ohmic resistance included therein across which input potential differences are established, an ohmic resistance, included therein across which potential differences to be derived from said network are established, and a unidirectionally conducting device connected across said last-mentioned resistance.

3. A high frequency receiving circuit having a single natural period, a detector associated with said circuit, and a low frequency circuit adapted to be energized by said detector, said low frequency circuit having a plurality of different natural periods, and means for damping the oscillations of said different natural periods.

4. In a signaling system, a receiving conductor, and a wave-responsive device, a circuit connecting said conductor and device, said circuit including a network comprising a plurality of sections, one of said sections comprising a resistance across which potentials to be applied to said network are impressed, and another of said sections including a resistance across which is directly connected said wave-responsive device.

5. In a receiving system, two thermionic devices, means connected between said devices comprising a recurrent network of a plurality of sections, each closed path in said network including a resistance of sufficient value to prevent free oscillations of a period determined by the constants of any path in said network.

6. In a wave transmission system, a plurally branched electrical network including inductance and capacity elements, an ohmic resistance in said network connected in the output circuit of a space discharge device.

for applying input energy to said network, and an ohmic resistance in said network constituting means for connecting said network to a device to which energy is to be supplied.

5 7. In a receiving system for eliminating static disturbances a network having a plurality of resonant sections, a resistance in each of said sections, two thermionic devices, each having an input circuit and an output circuit, one of said resistances being in the input circuit of one of said thermionic devices, the other of said resistances being in the output circuit of the other of said thermionic devices, and said network being located between said devices.

8. In a wave receiving system, a plurality of networks each consisting of a plurality of sections including inductance, capacity, and resistance, each network being adapted to transfer energy with equal facility from its input to its output terminals and vice versa, and a thermionic device adapted to connect the output terminals of one network 20 with the input terminals of a succeeding network.

9. In a receiving system for eliminating static disturbances, an energy transferring conductive system having a plurality of circuits, each including inductance, capacity and resistance, and having a plurality of degrees of freedom, and a unidirectionally conducting device between adjacent circuits of said conductive system for preventing re- 30 action between said circuits.

10. A receiving system comprising a high frequency line, a detector adapted to be supplied with energy from said line, a signaling device, and a circuit for connecting 40 said device to said detector, said circuit comprising a plurality of sectional networks, each section of at least one of said networks including resistance, inductance and capacity.

45 11. A receiving system comprising a high frequency line, a detector adapted to be supplied with energy from said line, a signaling device, and a circuit for connecting said device to said detector, said circuit comprising a plurality of critically damped resonant circuits, and means for preventing re- 50 action between said resonant circuits.

12. A receiving system comprising a high frequency line, a detector adapted to be supplied with energy from said line, a signaling device, a circuit for connecting said device to said detector, said circuit including a plurality of circuits each having a plurality of degrees of freedom, and means for 55 preventing the reaction of said circuits upon each other.

13. A receiving system comprising a receiving conductor, a detector adapted to be supplied with energy from said conductor, 60 a signaling device and a circuit for connect-

ing said device to said detector, said circuit comprising a plurality of circuits connected in tandem, each circuit comprising a plurality of sections and being so constructed as to transfer energy with equal facility in either direction between its input terminals and its output terminals, and a thermionic device between adjacent circuits for preventing reaction therebetween.

14. In a wave transmission system, a plurality branched electrical network including inductance and capacity elements, an ohmic resistance connecting two points in said network, connections from two points on said resistance to the output electrodes of a space discharge repeater, an ohmic resistance connecting two other points in said network, and connections from two points on said last-mentioned resistance to the input electrodes of a space discharge repeater.

15. A wave transmitting system including a plurality of the combinations described in claim 14 arranged in tandem.

16. A system comprising an electrical network consisting of a plurality of similar recurring sections, each section including inductance and capacity elements, an ohmic resistance in one section for deriving wave energy from said network, a space discharge repeater having its output circuit connected to the first of said resistances and a second space discharge repeater having its input circuit connected to the second of said resistances.

17. A radio receiving system comprising means for supplying and combining waves from a local source with received waves, and a periodic plurally branched electrical network having its branches conductively connected and comprising a plurality of identical closed paths each containing inductance and capacity, means for supplying the combined waves to said network, and means for receiving waves transmitted through said network.

18. A receiving system comprising means for supplying and combining waves from a local source with received waves, a plurality of plurally branched electrical networks each containing a plurality of closed paths including inductance and capacity elements, an asymmetrically conducting device between each adjacent pair of said networks, means for supplying the combined waves to the first of said networks and means for receiving waves transmitted through the last of said networks.

19. The method of receiving radio signals at a receiving station which comprises combining locally generated waves with the received waves, transmitting the resultant waves through a plurality of wave selecting circuits arranged in tandem, preventing the reaction of said circuits upon each other in a reverse direction through said circuits, and

translating into other than electrical energy at said station the waves transmitted through the last of said circuits.

20. A radio receiving system comprising means for combining locally generated waves with received waves and means for passing the resultant waves through a system including a tandem arrangement of the following elements in the order named: An 10 asymmetrically conducting repeater, a periodic electrical network comprising a plurality of closed sections including inductance and capacity, and an asymmetrically conducting repeater.
- 15 21. The method of selective reception and translation of electrical waves at a receiving station comprising receiving desired and disturbing waves together, combining other waves of a definite frequency therewith, selectively transmitting the resultant waves through a selective electrical network, amplifying the selectively transmitted output of said network, and selectively receiving and translating the amplified output waves into 25 other than electrical energy at said station.
22. A receiving station comprising means for combining other waves of a definite frequency and desired amplitude with received waves, a detector for detecting the combined 30 waves, an asymmetrically conducting device, a selective network, means for passing the detected waves in succession through said asymmetrically conducting device and said selective network and a low frequency responsive device controlled by the output of 35 said network.
23. A receiving station comprising in successive tandem arrangement at said station means for combining other waves of a definite frequency and desired amplitude with 40 received signaling and interfering waves, a detector for detecting the combined waves, a filter for selecting the detected waves, a low frequency wave controlled device at said 45 station for converting electrical energy into other energy, and an asymmetrically conducting repeater for transferring the waves passed by said filter to said device.
24. A receiving system comprising means 50 for combining other waves with received signaling and interfering waves and detecting the combined waves, a recurrent network comprising series and shunt reactance elements, two unidirectionally energy trans-

ferring devices between which said network 55 is connected, and means for supplying the combined detected waves to the first of said devices.

25. The method of selective reception comprising first mixing with the received 60 waves other waves of desired amplitude and constant frequency and successively amplifying and selectively attenuating the resultant waves.

26. A radio receiving system comprising 65 means for combining locally generated waves with received waves, a detector for detecting the combined waves and a filter for the detected waves, said filter consisting of recurring sections having shunt inductive 70 reactance and series capacity reactance elements.

27. A receiving station comprising a receiving conductor, a selective circuit through which received waves are transmitted, means 75 for combining with the waves transmitted by said circuit locally generated waves, a detector for detecting the combined waves, a signal indicating device, a selective circuit for conducting the detected waves to said 80 signal indicating device, and an unsymmetrically conducting device between said last mentioned selective circuit and said indicating device.

28. A receiving system comprising means 85 for combining locally generated waves with received waves, means for detecting the combined waves, a plurality of heavily damped selective circuits, an asymmetrically conducting device between each adjacent pair of 90 selective circuits, and means for passing the detected waves through said selective circuits and each conductive device interposed between adjacent pairs thereof.

29. A receiving system comprising means 95 for combining other waves of a definite frequency and desired amplitude with received waves, a wave distorting device for translating the combined waves, an asymmetrically conducting device, a selective iterative 100 electrical network, and means for passing the resultant waves in succession through said asymmetrically conducting device and said network.

In witness whereof, I hereunto subscribe 105 my name this 29th day of December A. D., 1916.

JOHN MILLS.
